UNITED STATES PATENT OFFICE.

EDWARD SCHAUERMANN, OF BALTIMORE, MARYLAND, ASSIGNOR TO THE HOLD FAST
CASTER CUP COMPANY, A COPARTNERSHIP CONSISTING OF SAID SCHAUERMANN
AND GEORGE A. RAMMING.

FLOOR-PROTECTING ATTACHMENT FOR FURNITURE.

1,221,225.

Specification of Letters Patent.

Patented Apr. 3, 1917.

Application filed February 4, 1915. Serial No. 6,110.

To all whom it may concern:

Be it known that I, EDWARD SCHAUERMANN, a citizen of the United States, residing at the city of Baltimore and State of Maryland, have invented certain new and useful Improvements in Floor-Protecting Attachments for Furniture; and I do declare the following to be a full, clear, and exact description of the invention, such as will enable others skilled in the art to which it appertains to make and use the same.

This invention relates to improvements in floor protecting and noise deadening attachments for furniture.

15 The object of the invention is to provide a silencing and floor protecting attachment for furniture which may be readily applied and removed and yet will remain securely in place when the article to which it is attached, is lifted.

20 Another object is to provide a device of this character which is so constructed as to prevent slipping of the article to which it is applied and which is especially designed for use on furniture equipped with casters.

25 With the above and other objects in view, the invention consists of certain novel features of construction and combination herein described and claimed and shown in the drawings wherein:—

30 Figure 1 represents a front elevation of a portion of a piano equipped with this improved attachment;

Fig. 2 is an enlarged detail showing the 35 attachment in transverse section;

Fig. 3 is a similar view taken on a plane at right angles to Fig. 2;

40 Fig. 4 is a perspective view of the attachment with the parts thereof detached and arranged in juxtaposition ready for assembling;

Fig. 5 is a detail perspective view showing a slightly different form of attaching plate;

45 Fig. 6 is a plan view showing the plate in operative position in the cap.

Fig. 7 is a detail view partly in section showing another way in which my invention can be used.

50 In the embodiment illustrated, the device is shown applied to a piano P but it is to be understood that it may be used on furniture of all kinds having either legs or casters, or both but is especially designed for use on

casters. The silencing and anti-scratching device comprising this invention, is shown 55 in the form of a cup-shaped member or cap 1 having a flat surface engaging face or bottom 2 which is designed to fit snugly against the floor to hold the device against slipping after the article on which it is mounted, has 60 been positioned and a caster wheel receiving socket 2' in its top. This cap 1 may be constructed of wood, rubber or any suitable non-scratching material such as could be moved over hard wood floors without marring them. 65

Mounted in the cap is a plate 3 which is annular in form and provided with a central opening 4 and on its edge at diametrically opposite points with spring clamping fingers or plates 5. The annular plate 3 is 70 of a size to snugly fit the walls of the opening 2' in the cap as shown in Fig. 3 and if desired, it may be more effectively secured by the use of screws passed through openings in the plate as will be readily understood 75 on reference to Figs. 3 and 4. The spring clamping plates 5 are adapted to frictionally engage and adhere to the article to which the device is applied. As shown they engage a caster which consists of the usual 80 shank or fork S swiveled to an article of furniture P and a roller or wheel C journaled in the shank. Said plates 5 are of a length to project above the upper surface of the cap 1 and normally spring inwardly into 85 converging relation so that they may effectively grip a portion of the caster at a point of less width or thickness than some point below the upper extremities of the plates as will be understood on reference to Fig. 2 90

which shows said plates 5 gripping the shank S at a point above the journal of the caster-wheel C. By having the plates 5 project above the top of the cap 1 and of a length greater than the radius of the caster wheel C 95 as shown in Fig. 2, they will be able to have their upper extremities grip some portion of the caster which is of less width or thickness than some point below and then will thus effectively hold the device in position. 100 To aid the clamping plates 5 in gripping the caster, the opening 4 in the plates 3 is preferably of a size sufficient to receive the caster wheel C which latter tends to prevent shifting of the cap on the caster. When applied, the plates 5 are under tension so that 105

the entire device will cling to the leg or 5 caster when the article of furniture is lifted, thus preventing the displacement of the device from the article of furniture when it is moved. This is especially desirable when 10 the invention is applied to a heavy article such as a piano or to a chair or table that is frequently moved about the room. These clamping plates 5 are preferably rectangular in form to afford an extended engaging 15 surface and they may be flat or curved transversely as hereinafter described.

In the form shown in Figs. 5 and 6, the 20 plate 3' is constructed similarly to the plate 3 of the other figures, the only difference being that the spring clamping fingers or plates 5' which project upwardly from the periphery thereof, are curved transversely to adapt them to snugly fit the walls of the 25 cap 1, thereby frictionally securing said plate within said cap and avoiding the necessity of using attaching screws.

The use of this cap will be obvious without a detail description, it being of course 30 understood that the plate 3 is first secured in the cap 1 and the leg or caster to which it is to be applied is inserted in the cap between the fingers 5, with the bottom of the leg or the lower edge of the caster resting in the opening or seat 4 and with the spring 35 plates 5 engaging some portion of the leg or caster at opposite points as heretofore described.

In Fig. 7 of the drawings the spring 40 plates 5 are shown engaging the periphery of the caster wheel C, the upper portions

of said plates engaging the wheel at a point above its horizontal axis so that the device will be effectively retained in position.

I claim as my invention:—

The herein described floor protector to snap onto furniture casters comprising a cap composed of non-scratching material having a flat floor engaging bottom and provided in its top with a caster wheel receiving 45 socket, said socket having a flat bottom and an upright side wall, and a retaining member formed from a plate of resilient sheet metal having a central portion conforming to the shape of the socket and fitting flat 50 against the bottom thereof and with its edge engaging the side wall of said socket, rectangular spring clamping plates formed integral with the edge of said central plate portion at diametrically opposite points and inclined upwardly and inwardly at oblique angles to said central plate portion, said clamping plates projecting above the top of the 55 cap and being of a length greater than the radius of the caster wheel inserted in said 60 socket to provide for the effective clamping engagement of the upper extremities of said plates with a portion of the caster at points above the horizontal axis of the caster wheel, for the purpose set forth.

In testimony whereof I have hereunto set my hand in presence of two subscribing witnesses.

EDWARD SCHAUERMANN.
